BREAST ROLL TRANSFER MECHANISM FOR FOURDRINIER PAPER MAKING MACHINES

Original Filed July 23, 1924 2 Sheets-Sheet 2

UNITED STATES PATENT OFFICE.

EARL E. BERRY, OF BELOIT, WISCONSIN, ASSIGNOR TO BELOIT IRON WORKS, A CORPORATION OF WISCONSIN.

BREAST-ROLL TRANSFER MECHANISM FOR FOURDRINIER PAPER-MAKING MACHINES.

Application filed July 23, 1924, Serial No. 727,638. Renewed April 29, 1926.

This invention relates to a paper making machine and more particularly to the breast roll end of a Fourdrinier wherein the table is adapted to be moved transversely out of the side of the machine into a position to permit the wire to be replaced by a new one or repaired as the case may be.

It is an object of this invention to provide an improved Fourdrinier breast roll mounting and mechanisms whereby the breast roll and its bearings may be transferred as a unit onto the table for removal therewith when it becomes necessary to replace the Fourdrinier wire.

It is also an object of the invention to provide a breast roll mounting for a Fourdrinier, said mounting being arranged to permit the breast roll and its bearings to be removed as a unit and transferred over a temporary support onto a bracket mounted on the table whereby the breast roll may be moved out of the side of the machine with the table to permit replacement of the Fourdrinier wire.

It is an important object of this invention to provide a simple and improved breast roll mounting for the Fourdrinier end of a paper making machine, said mounting being arranged to permit release of the breast roll so that the same may be rolled across a removable bridge onto a table support for removal with the table to permit replacement of the Fourdrinier wire.

Other and further important objects of this invention will be apparent from the disclosures in the specification and drawings.

The invention (in a preferred form) is illustrated in the drawings and hereinafter more fully described.

On the drawings:

Figure 1 is a fragmentary front side elevation of the breast roll end of a Fourdrinier machine illustrating the improved breast roll mounting embodying the principles of this invention.

Figure 2 is a fragmentary sectional view taken on line 2—2 of Figure 1.

Figure 3 is a fragmentary front side view similar to Figure 1 showing the breast roll

removed from its mounting and supported on the table brackets.

Figure 4 is a top plan view of the bridge bar and the table bracket.

As shown on the drawings:

The reference numeral 1 indicates the base I-beams which form a base section for the Fourdrinier end of a paper making machine. Mounted on one end of the base section (although not shown) is a head or flow box to the sides of which are secured the ends of supporting strips or springs 2. The outer end of each spring 2 is secured to a breast roll supporting bracket 3 of semi-circular shape and having the lower end 4 rigidly mounted upon a pair of upright wooden strips or springs 5. The lower ends of the springs 5 are secured to base pieces 6 bolted to the base members 1. The lower end 4 of each supporting bracket 3 is provided with an integral shelf plate 7 through which an adjusting screw 8 projects. Openings are provided in the side flanges of the lower end 4 of each bracket 3 to removably receive retaining pins 9. Attached to the upper portion of each supporting bracket 3 by means of a bolt 10 is a curved clamp or arm 11.

A breast roll 12 forms part of the machine and is provided with journals which are engaged in bearings 13. Each breast roll bearing 13 has formed thereon a peripheral gear 14. A squared shank or stub shaft 15 is formed on each bearing 13 to receive the apertured head of a wrench handle or crank arm.

A set-screw 28 is provided in each bearing 13 for the purpose of locking the bearings to the journals of the breast roll to permit rolling of the breast roll together with the bearings as a unit when crank arms are engaged on the squared stub shaft 15 of the bearings.

Forming part of the Fourdrinier is a table 16 upon which the table rolls 17 are supported. The table 16 together with the table rolls 17 form a unit of a type which is adapted to be moved out through the front side of the Fourdrinier section to permit replace-

ment of the wire. Rigidly secured to the end of the table 16 are brackets 18 each having a groove 19 in which teeth 19^a are provided to form a rack. A bottom extension plate 20 is integrally formed on each bracket 18 through which an adjusting screw 21 projects. Apertured side flanges 23 are integrally formed on the bracket 18 at the sides of the plate 20 and removable support pins 24.

When it is desired to replace the Fourdrinier wire, a bridge beam 25 is supported in place on each side of the machine by means of the pins 9 and the pins 24. The bridge beams 25 span the space between the bracket 18 and the lower end 4 of the supporting bracket 3. The screws 8 and 21 are adapted to be adjusted to adjust the bridge beams. Formed on the top of each bridge beam is a row of teeth to form a rack 26 for co-action with the teeth of the gear 14. The teeth 19^a on the brackets 18 afford a continuation of the rack 26.

The operation is as follows:

When the Fourdrinier wire is to be removed from the machine the bridge beams 25 are mounted in place as illustrated in Figure 1 supported by the pins 9 and 24. Adjustment of the bridge beams is accomplished by adjusting the screws 8 and 21 respectively until the bridge beams are properly positioned connecting the table rails 16 with the lower ends 4 of the supporting brackets 3.

The locking set screws 28 are adjusted to lock the bearings to the journals of the roll. The bolts 10 are next loosened and the clamps 11 are pushed upwardly and secured in the release position of Figure 3 thereby releasing the breast roll 12 and its supporting bearings 13. By applying crank arms to the squared stub shafts 15 of the breast roll bearings the breast roll together with its bearings is rolled out of the supporting brackets 3 as a unit with the gear teeth 14 meshing with the rack teeth 26 and the rack teeth 19^a. The breast roll 12 and its bearings 13 is thus rolled across the bridge beams 25 as a unit onto the brackets 18 as illustrated in Fig. 3. After the bridge beams are removed wedge members or stop dogs 27 are engaged behind the pins 24 and beneath the bearings 13 of the breast roll 12. The breast roll unit is thus held in place on the brackets 18 after which the table carrying the breast roll unit are moved as a unit out through the front side of the Fourdrinier section to permit a new wire to be mounted in place in the machine.

While set screws 28 are described as a means for locking the bearings to the journals of the breast roll, pins or any other suitable locking means may be used.

I am aware that many changes may be made, and numerous details of construction may be varied through a wide range without

departing from the principles of this invention, and I therefore do not purpose limiting the patent granted hereon, otherwise than necessitated by the prior art.

I claim as my invention:

1. In a Fourdrinier section of a paper making machine the combination with breast roll supports, of a table, brackets secured to the table, a breast roll supported by the breast roll supports, and bridge members 75 adapted to connect the breast roll supports with said brackets to permit the breast roll to be rolled over onto said brackets for removal from the Fourdrinier section with the table.

2. In a Fourdrinier section the combination with breast roll supports, of a table, and removable means for bridging the space between the supports and said table.

3. In a Fourdrinier section the combination with breast roll supports, of a table spaced therefrom, brackets on said table, and bridge members removably supported on said supports and on said brackets.

4. In a Fourdrinier section the combination with breast roll supports, a breast roll, bearings therefor adapted to seat in said supports, and clamping means movably mounted on said supports adapted to removably engage said bearings to hold the breast 95 roll in operating position.

5. In a Fourdrinier section the combination with breast roll supports, of a breast roll, bearings therefor, adjustable means on the supports for engaging the bearings to hold the breast roll in position, a table separated from the supports, brackets secured to the ends of said table, and bridge members 100 removably supported on the supports and on said brackets to permit the breast roll 105 to be transferred onto said brackets when said adjustable means are released.

6. In a Fourdrinier section the combination with breast roll supports, of a breast roll, bearings therefor adapted to be seated 110 in said supports, gears formed on said bearings, a table, brackets mounted thereon, clamps adjustably mounted on said supports for holding the bearings in place, brackets secured to the table, and rack bridge members 115 removably supported on said supports and on said brackets adapted when the clamps are released to permit the bearing gears to co-act with said bridge members to convey the breast roll over onto the table 120 brackets.

7. In a Fourdrinier section the combination with breast roll supports, of a table, rack members removably connecting the supports with said table, a breast roll, bearings for the breast roll supported in said supports, journals for the breast roll within said bearings, means for locking the bearings to said journals, and gears formed on said bearings adapted to co-act with said 125 130

- rack members when the bearings are turned to transfer the breast roll from the breast roll supports over the rack members onto the table.
8. A Fourdrinier section comprising a base, a breast roll and a table above said base, members for independently supporting the breast roll and said table on said base, rack brackets mounted on said table, rack members adapted to removably bridge the space between the table and the members supporting the breast roll, and geared bearings for the breast roll adapted to co-act with the rack members and said rack brackets to permit the breast roll to be transferred onto the table.
9. A Fourdrinier section comprising a base, a breast roll and a table above the base, independent supports on said base for the breast roll and for said table, bridge members removably connecting the breast roll supports with the table to permit the breast roll to be transferred across the bridge members onto the table, and stop means for holding the breast roll in position on said table.
10. In a Fourdrinier section the combination with a breast roll, bearings therefor, supports for the bearings, a table, brackets mounted thereon, bridge members adapted to be removably mounted between the bearing supports and said brackets to permit the breast roll to be transferred over onto the brackets, means for adjusting the bridge members, and stops adapted to be engaged on the brackets to hold the transferred breast roll in position on said brackets.
11. In a Fourdrinier section the combination with breast roll supports, of a table spaced therefrom, brackets on said table, bridge members removably connecting said breast roll supports and said brackets, a breast roll, bearings therefor normally mounted in said supports, journals for the breast rolls in said bearings, and means for locking the breast roll bearings with said journals to permit the bearings and said breast roll to be transferred as a unit across the bridge members onto said brackets.
12. In a Fourdrinier paper making machine the combination with a breast roll, bearings therefor, journals in said bearings, supports for said bearings, and means for removably locking said bearings with said journals to permit the breast and its bearings to be removed from said supports as a unit.
13. In a Fourdrinier paper making machine the combination with supports, of a breast roll, bearings for said breast roll supported in said supports, journals in said bearings, means for locking said bearings with said journals, a table, brackets mounted thereon, bridge members removably connecting said brackets with said breast roll sup-
- ports, and extensions formed on said breast roll bearings adapted to be engaged by crank means to permit the breast roll and bearings to be transferred as a unit from the breast roll supports across said bridge members onto the table brackets.
14. In a paper making machine a table structure, a breast roll and bearings therefor, supported separately therefrom, and means for transferring the breast roll and its bearings as a unit to the table structure.
15. In a Fourdrinier machine, the combination of a laterally removable table and breast roll supports on which the breast roll is removably mounted, and a bridge structure along which the breast roll may be moved between the table and breast roll supports, said table being provided with a support upon which the breast roll may be moved and on which it may rest during the removal and return of the table.
16. In a Fourdrinier machine, the combination of a laterally removable table and separated breast roll supports on which the breast roll is removably mounted, and a supporting structure along which the breast roll may be moved between the table and breast roll supports, said table being provided with a support in the form of a projecting shelf or ledge upon which the breast roll may be moved and on which it may rest during the removal and return of the table.
17. In a Fourdrinier machine, the combination of a laterally removable table and separated breast roll supports on which the breast roll is removably mounted, and a supporting structure along which the breast roll may be moved between the table and breast roll supports, said table being provided with a support in the form of a projecting shelf or ledge upon which the breast roll may be moved and on which it may rest during the removal and return of the table, said breast roll supports having means whereby they may be opened at the side toward the table to permit the breast roll to be moved out of the bearings and along said support.
18. In a Fourdrinier machine, the combination of a laterally removable table and separated breast roll supports on which the breast roll is removably mounted, and a supporting structure along which the breast roll may be moved between the table and breast roll supports, said table being provided with a support in the form of a projecting shelf or ledge upon which the breast roll may be moved and on which it may rest during the removal and return of the table, said breast roll supports having means whereby they may be opened at the side toward the table to permit the breast roll to be moved out of the bearings and along

said support, said means comprising an adjustable slide normally adapted to hold the breast roll in position but arranged to slide out of the way to allow the breast roll to be removed.

19. In a Fourdrinier machine, the combination of a laterally removable table and separated breast roll supports on which the breast roll is removably mounted, track 10 members extending between the breast roll supports and the table along which track members the breast roll may roll, and a support on the table to receive and hold the breast roll when rolled to the table from 15 said supports.

20. In a Fourdrinier machine, the combination of a laterally removable table and separated breast roll supports on which the breast roll is removably mounted, track 20 members extending between the breast roll supports and the table, along which track members the breast roll may roll, a support on the table to receive and hold the breast roll when rolled to the table from said supports, and means for adjusting said track 25 members relatively to said breast roll supports.

21. In a Fourdrinier machine, the combination of a laterally removable table and 30 separated breast roll supports on which the breast roll is removably mounted, track members extending between the breast roll supports and the table, along which track members the breast roll may roll, a support 35 on the table to receive and hold the breast roll when rolled to the table from said supports, and means for adjusting said track members relatively to said table.

22. In a Fourdrinier machine, the combination of a laterally removable table and 40 separated breast roll supports on which the breast roll is removably mounted, track members extending between the breast roll supports and the table, along which track 45 members the breast roll may roll, a support on the table to receive and hold the breast roll when rolled to the table from said supports, and means for adjusting said track 50 members relatively to said supports and to said table.

23. In a Fourdrinier machine, the combination of a laterally removable table and separated breast roll supports on which the breast roll is removably mounted, track 55 members extending between the breast roll support and the table, along which track members the breast roll may roll, a support on the table to receive and hold the breast roll when rolled to the table from said supports, and means for adjusting said track 60 members relatively to said breast roll supports, said adjusting means comprising set screws adapted to adjust the ends of said track members at said breast roll supports.

24. In a Fourdrinier machine, the combi-

nation of a laterally removable table and separated breast roll supports on which the breast roll is removably mounted, track 70 members extending between the breast roll supports and the table, along which track members the breast roll may roll, a support on the table to receive and hold the breast roll when rolled to the table from said supports, and means for adjusting said track members relatively to said table, said adjusting means comprising set screws adapted to adjust the table ends of said track members.

25. In a Fourdrinier machine, the combination of a laterally removable table and 80 separated breast roll supports on which the breast roll is removably mounted, track members extending between the breast roll supports and the table, along which track 85 members the breast roll may roll, a support on the table to receive and hold the breast roll when rolled to the table from said supports, and means for adjusting said track members relatively to said supports and to said table, said adjusting means comprising 90 set screws at the ends of said track members.

26. In a Fourdrinier machine, the combination of a laterally removable table and separated breast roll supports on which the breast roll is removably mounted, track 95 members extending between the breast roll supports and the table along which track members the breast roll may roll, and a support on the table to receive and hold the breast roll when rolled to the table from 100 said supports, and means for turning the breast roll so as to roll it along said track members.

27. In a Fourdrinier machine, the combination of a laterally removable table and 105 separated breast roll supports on which the breast roll is removably mounted, track members extending between the breast roll supports and the table along which track members the breast roll may roll, and a support 110 on the table to receive and hold the breast roll when rolled to the table from said supports, said track members being provided with rack teeth and the breast roll being provided with cooperating toothed 115 wheels or gears.

28. In a Fourdrinier machine, the combination of a removable table and breast roll supports on which the breast roll is removably mounted, a bridge structure along 120 which the breast roll may travel, and a rest or holder on the table to receive the breast roll from said bridge structure, said bridge structure being substantially horizontal so as to permit ready movement of the breast 125 roll from its supports to the table and back again.

29. In a Fourdrinier machine, the combination of a laterally removable table and breast roll supports on which the breast 130

- roll is removably mounted, track members between the breast roll supports and the table along which track members the breast roll may roll, and a rest or holder on the 5 table to receive the breast roll from said track members, said track members being substantially horizontal to permit ready rolling of the breast roll from its supports to the table and back again, and said table 10 breast roll holder or rest being a substantially horizontal platform to readily receive the breast roll from said track members.
30. In a Fourdrinier machine, the combination of a laterally removable table and 15 separated breast roll supports on which the breast roll is removably mounted, track members extending between the breast roll supports and the table along which track members the breast roll may roll, and a sup- 20 port on the table to receive and hold the breast roll when rolled to the table from said supports, said track members being mounted in a substantially horizontal position to permit ready rolling of the breast 25 roll from its supports to the table and back again, and said table breast roll support being a substantially horizontal platform to readily receive the breast roll from said track members, and means for holding said 30 breast roll in positions on said platform.
31. In a Fourdrinier machine, the combination of a laterally removable table and separated breast roll supports on which the breast roll is removably mounted, track 35 members extending between the breast roll supports and the table along which track members the breast roll may roll, and a sup-
- port on the table to receive and hold the breast roll when rolled to the table from said supports, and means for holding the 40 breast roll in position on said table breast roll support.
32. A Fourdrinier machine having breast roll supports provided with means for removably mounting the breast roll and its 45 bearings as a unitary structure and also having track members along which said breast roll with its bearings may be rolled for removal from the breast roll supports.
33. A Fourdrinier machine having breast 50 roll supports provided with means for removably mounting the breast roll, and also having a supporting structure along which the breast roll may roll when removed from said supports.
34. In a Fourdrinier machine, the combination with the table and breast roll supports, the latter being provided with mounting means openable toward the table to permit the removal of the breast roll, and a 55 supporting structure along which the breast roll may be moved between its supports and the table.
35. In a Fourdrinier machine, the combination with breast roll supports having mounting means for the breast roll openable at one side and a supporting structure arranged to permit the breast roll to travel upon and along it when removed from said supports by means of the open sides thereof. 60
- In testimony whereof I have hereunto 65 subscribed my name.

EARL E. BERRY.
